FIRE-CONTROL MECHANISM FOR FIREARMS

Harry H. Sefried, II, New Haven, Conn., assignor to Olin Industries, Inc., New Haven, Conn., a corporation of Delaware

Application July 15, 1948, Serial No. 38,817

7 Claims. (Cl. 42—69)

1

The present invention relates in general to firearms and more especially to improvements in fire-control mechanisms for bolt-action firearms.

An object of the invention is to provide a bolt-action firearms with fire-control mechanism of superior durability and reliability.

A further object of the invention is to provide a superior fire-control mechanism for bolt-action firearms wherein the trigger-pull is characterized by its uniformity, smoothness of operation and substantially imperceptible movement.

A still further object of the invention is to provide a superior fire-control mechanism for bolt-action firearms wherein a movement-multiplying lever mechanism is interposed between the trigger and sear, whereby substantially imperceptible movement of the trigger will suffice to transmit relatively large movement to the sear for releasing the firing-plunger.

A still further object of the invention is to provide a bolt-action firearm having a spring-actuated firing-plunger with fire-control mechanism including a sear which is arranged normally to hold the firing-plunger in cocked position but which, when released, is urged out of engagement with the firing-plunger by the force of the firing-plunger spring.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a broken side elevation in section of an upturn and pull-back bolt-action firearm embodying the present invention, with the stock and associated parts omitted;

Fig. 2 is a broken end elevation on section line 2—2 of Fig. 1 showing the position of the bolt-operating handle when the breech-bolt is in its locked position and the firing-plunger cocked, as shown in Fig. 1;

Fig. 3 is a broken side elevation in section of the firearm of Fig. 1 showing the relative positions of the elements of the fire-control mechanism following release of the firing-plunger;

Fig. 4 is a broken end elevation in section on line 4—4 of Fig. 3;

Fig. 5 is a broken side elevation of the firearm showing the manually-operated safety-lever for locking and releasing the sear-latch of the fire-control mechanism;

Fig. 6 is a broken perspective view of the trigger of the fire-control mechanism;

2

Fig. 7 is a perspective view of the sear of the fire-control mechanism of this invention;

Fig. 8 is a perspective view of the sear-latch of the fire-control mechanism;

5 Fig. 9 is a perspective view of the transmitting-member of the fire-control mechanism of this invention; and

10 Fig. 10 is a perspective view of a modification of the fire-control mechanism of this invention including a broken portion of the firing-plunger.

The particular firearm herein chosen for illustrating the present invention is of the so-called "upturn and pull-back bolt-action" type, and includes a receiver 15 of substantially-tubular form 15 provided at its forward end with an interiorly-threaded aperture for receiving the rear end of a barrel 16 having a cartridge-chamber 17 therein. The receiver 15 is also provided with an axial bolt-receiving passage 18, the forward upper portion of which is intersected by a loading-and-ejection opening 19.

Mounted in the bolt-receiving passage 18 of the receiver 15 with capacity for reciprocation therein, is a cylindrical bolt 20 having an axial firing-plunger passage 21 therein intersected at its forward end by a relatively small substantially-conical eccentric passage 22. Projectable through the said passage 22 is the firing-point 23 of a firing-plunger 24 mounted in the passage 21 of the bolt 20.

30 The rear portion of the firing-plunger 24 is of tubular form in cross section and provides a firing-spring chamber 25 adapted to receive a firing-spring 26 which thrusts at its forward end against the front wall 27 of the firing-spring chamber 25.

35 The rear end of the firing-spring 26 is seated against a pin 28 securely mounted in and extending transversely through the reduced cylindrical rear-end portion 29 of the bolt 20. The pin 28 is adapted to extend through longitudinal clearance-slots 30, respectively formed in the top and bottom walls of the rear tubular portion of the firing-plunger 24 so that the said firing-plunger may reciprocate in the longitudinal passage 21 of the bolt 20 independently thereof, but at the same time be prevented from rotative movement with respect thereto.

40 As shown, the rear end of the firing-plunger 24 may be provided with a head 31 having forwardly-extending nibs 32 adapted to enter complementary notches 33 in the rear end of a bolt-operating sleeve 34 which is mounted for capacity for turning movement upon the reduced cylindrical rear-end portion 29 of the bolt 20, the bolt-operating sleeve 34 being provided with an integral laterally-offset handle 35 terminating in a ball-grip 36.

At a portion substantially intermediate its respective opposite ends, the underside of the firing-plunger 24 is cut away transversely as at 37, to provide a substantially-vertical forwardly-facing cocking-shoulder 38 which is adapted to be engaged, when the firearm is cocked, by the rearwardly-facing shoulder 39 of a sear-nose 40 vertically upstanding from the forward end of a pivotal sear 41. The sear 41 is pivotally mounted adjacent its rear end by means of a transverse pivot-pin 42 in the vertical passage 43 (see Fig. 2) of a trigger-plate member, indicated generally at 44. The latter comprises two substantially-rectangular side-plates 45 and 46 held in spaced-parallel relationship by transverse spacer-beads 47 secured by rivets 48 between the lower edges of the plates, as shown in Fig. 10; and a spacer-block 49 mounted therebetween adjacent the upper rear corners of the plates, the block 49 having a vertical internally-threaded aperture 50 for the purpose hereinafter described. The trigger-plate member 44 is adapted to be secured at its upper end in a vertical aperture in the bottom of the receiver by means of a screw 51 which is mounted in an aperture 52 in the rear end of the receiver and engaged in the internally-threaded aperture 50 in the rear end of the spacer-block; and by an assembly-pin 53 extending transversely through the bottom of the receiver and through aligned apertures in the upper edges of the trigger-plate. As shown especially well in Figs. 1, 3 and 4, the assembly-pin 53 extends through an aperture 54 in the sear 41, the diameter of the aperture 54 being greater than the diameter of the pin 53 whereby the sear is enabled to pivot freely about its pivot-pin 42 in a vertical plane within limits defined by the diameter of the aperture 54. As shown especially well in Figs. 1 and 3, the sear-nose 40 of the sear is adapted to project upwardly through a longitudinal clearance-slot 55 in the underside of the bolt, for engagement of its substantially-vertical rearwardly-facing shoulder 39 with the forwardly-facing cocking-shoulder 38 of the firing-plunger 24, the sear-nose 40 being forwardly of the pivot-pin 42 of the sear and the assembly-pin 53 of the trigger-plate. Depending from the sear rearwardly of its pivot-pin 42 is an integral lever-arm 56 which is disposed at an angle to the longitudinal axis of the sear and is adapted to be engaged by a finger of the trigger for lowering the sear-nose 40 out of the clearance-slot 55 of the bolt, for the purpose hereinafter described.

Formed on the underside of the sear forwardly of its pivot-pin 42 and immediately rearwardly of its transverse aperture 54, is an arcuate substantially-vertical recess 57 which is adapted to accommodate the upper end of the resilient upper arm 58 of a safety-pin type spring, indicated generally at 59, the eye of which may be engaged on a transverse pin 60 mounted in the trigger-plate forwardly of the sear pivot-pin 42 and rearwardly of the recess 57 of the sear. The lower arm 61 of the spring 59 extends forwardly and is engaged at its forward extremity over one of the spacer-beads 47 of the trigger-plate. As a consequence of this construction, the upper arm 58 of the spring 59 exerts a constant force against the underside of the sear forwardly of its pivot-pin 42, normally to hold the sear-nose 40 in an elevated position. Formed integrally on the bottom forward corner of the sear and rearwardly of the front edge of the sear-nose 40, is a forwardly-projecting sear-lug 62, the lug being

generally of rectangular configuration with its upper edge 63 inclined slightly downwardly and rearwardly and its lower edge 64 inclined slightly upwardly and rearwardly with respect to the front edge of the lug.

The aforesaid sear-lug is adapted normally, that is to say, when the shoulder 39 of the sear-nose is in engagement with the cocking-shoulder 38 of the firing-pin, to engage in a substantially-rectangular rearwardly-facing notch 65 formed in the rear edge of a sear-latch 66. The latter is pivotally supported at its upper end in the trigger-plate 44 by a transverse pivot-pin 67 so as to swing in the vertical passage 43 thereof, the bottom edge 68 of the sear-latch being arcuate and intersecting the lower end of the front edge of the sear-latch to form a sharp corner or toe 69.

The toe 69 of the sear-latch is adapted normally to engage against the rearwardly-facing shoulder 70 of a transmitting-member 71 which comprises a lever pivoted at its rear end in the passage 43 of the trigger-plate by a transverse pin 72 for vertical swinging movement therein, its shoulder 70 being normally held up resiliently in the path of the toe 69 of the sear-latch by means of a coil-spring 73. The latter is supported in the bottom of the trigger-plate passage 43 on the upwardly-projecting pilot 74 of a spring-tensioning screw 75 threadedly secured therein, the upper end of the spring 73 engaging in a recess in the underside of the transmitting-lever 71. A second screw 76 is threadedly mounted in the bottom of the passage 43 of the trigger-plate 44 forwardly of the spring-tensioning screw 75 for vertical adjustment therein, its upper end being disposed immediately beneath the underside of the transmitting-lever 71 forwardly of its pivot 72 to limit the downward or clockwise swinging movement thereof. A third adjusting-screw is shown at 77 similarly mounted in the vertical passage 43 of the trigger-plate 44 and at the forward extremity thereof for vertical adjustment therein, the screw 77 carrying a spring-pilot 78 at its upper end on which is mounted a buffer-spring 79. The upper end of the latter engages against a fixed stop 80 at the upper end of the pilot 78, while the lower end of the spring 79 engages against a washer 81 mounted for vertical movement on the pilot 78, the washer 81 being of a diameter such as to overlie the upper forward corner of the transmitting-lever 71 so as to restrain or dampen the upward movement thereof, for the purpose hereinafter described.

Formed on the upper edge of the transmitting-lever 71 at its rear end, is an integral upwardly-projecting knee 82, the back edge of which slopes upwardly and forwardly to provide a trigger-engaging portion 83 thereon slightly forward of its pivot-pin 72 for engagement by the upper end of a finger 84 of the trigger. The trigger is indicated generally at 85 and comprises a substantially-triangular body-portion 86 having a transverse aperture adjacent the lower end thereof and substantially intermediate its front and rear edges to receive a pin 87 for pivotally mounting the trigger in the vertical passage 43 between the respective sides 45 and 46 of the trigger-plate 44. Clearance-recesses are provided in opposite sides of the trigger-body 86 adjacent the upper rear corner thereof, to form a web 88 which is provided with a transverse aperture rearwardly of the trigger pivot-pin for connecting the lower end of a trigger-spring 89

thereto. The upper end of the spring 89 is engaged on a transverse pin 90 which extends between opposite sides of the trigger-plate 44, above and rearwardly of the pivot-pin of the trigger whereby the force of the spring 89 serves to continuously urge the trigger, and more especially its finger 84, forwardly in a clockwise direction into engagement with the trigger-engaging surface 83 of the knee 82 of the transmitting-member 71. Actuation of the trigger 10 85 is effected by means of the finger-piece 91 formed integrally or otherwise attached to the lower edge of the body-portion 86 of the trigger.

Assuming that the breech-bolt, firing-pin and fire-control elements are in their respective positions as shown in Fig. 1, wherein the breech-bolt is closed and locked, as indicated by the position of the operating-handle 35 of Fig. 2, and that the firing-plunger 24 is held in its cocked position by engagement of the sear-nose, and more particularly the substantially-vertical rearwardly-facing shoulder 39 thereof, with the transverse cocking-shoulder 38 of the firing-pin, then the force of the compressed spring 26 of the firing-pin will be directed against the substantially-vertical shoulder 39 of the sear-nose on a substantially-horizontal line above the pivot-pin 42 of the sear, as a consequence of which a turning moment force will act on the shoulder 39 of the sear to pivot the sear in a clockwise direction. The latter is positively held, however, from pivoting clockwise by engagement of the lower edge 64 of its lug 62 with the lower shoulder of the notch 65 in the sear-latch 66, the lower shoulder of the notch 65 being substantially perpendicular to the force transmitted thereto by the sear-lug. Moreover, since the lower shoulder of the notch 65 is below and rearwardly of the pivot-pin 67 of the sear-latch, the force exerted thereon by the sear-lug 62 tends to rotate the sear-latch in a counterclockwise direction and consequently, with the parts in the position shown in Fig. 1, to hold the toe 69 of the sear-latch in locked engagement with the shoulder 70 of the pivoted transmitting-member 71; thus, the sear is effectively precluded from disengaging the cocked firing-plunger 24.

To fire the piece, the trigger 91 is pulled rearwardly, whereupon its finger 84 exerts pressure against the knee 82 of the resiliently-held pivotally-mounted transmitting-member 71, to pivot the latter in a clockwise direction and withdraw its shoulder 70 from engagement with the toe 69 of the sear-latch 66. Immediately upon release of the toe 69 of the latter, the force exerted by the sear-lug 62 on the lower shoulder of the sear-latch, swings the latter forwardly thereby disengaging the sear-lug therefrom, whereupon the sear swings downward freely in a clockwise direction thereby lowering the sear-shoulder 39 from engagement with the cocking-shoulder 38 of the firing-plunger 24. Thus, the firing-plunger is released and moves forwardly forcefully under the compression force of the firing-plunger spring 26 to fire the cartridge in the chamber 17 of the barrel. Following discharge of the firearm, the operator will release the trigger, whereupon the force of the compressed spring 73 of the transmitting-lever, being greater than the force of the relatively-light trigger-spring 89, tends to urge the forward end, and more especially the latching-shoulder 70 of the transmitting-lever, upwardly into position for re-engagement with the toe of the sear-latch and to pivot the trigger-finger 91 forwardly.

However, by reference to Fig. 3 it will be seen that immediately following the discharge of the firearm, the underside of the firing-plunger rides over the upper edge of the sear-nose 40 so as to effectively hold the sear-nose in a lowered position, in which position the sear-lug 62 is displaced below the notch 65 of the sear-latch, with the front edge of the lug engaging the rear edge of the latter, whereby the latch is positively held in its forward position overlying the forward end of the transmitting-lever 71. Consequently, the elements of the fire-control mechanism are effectively locked in inoperative position until the breech-bolt is unlocked and moved rearwardly in the receiver. This is done by grasping the breech-bolt handle 35 and swinging the handle upwardly to a substantially-vertical position to unlock the bolt and simultaneously to cock the firing-plunger 24, in the characteristic manner of an upturn and pull-back type of bolt-action firearm. Thereafter, the operator pulls rearwardly on the operating-handle to move the bolt rearwardly in the receiver for extracting the fired cartridge and to permit loading a fresh cartridge into the chamber of the barrel. During the rearward movement of the bolt and firing-plunger, the undersides thereof ride off of the upper edge of the sear-nose 40 which is then free to move upwardly into the clearance-space provided in the receiver by the rearwardly-moving breech-bolt and firing-plunger, the upper movement of the sear-nose being limited by engagement of the lower edge of the clearance-aperture 54 of the sear with the transverse assembly-pin 53. With the upward movement of the sear, its lug 62, and more particularly the upper edge 63 thereof, moves up into engagement with the upper shoulder of the notch 65 in the sear-latch 66 to pivot the latter in a clockwise direction and thus retract its toe 69 to a position rearwardly of the shoulder 70 of the pivoted transmitting-member 71. The latter being freed by the rearwardly-pivoting sear-latch, is then swung upwardly by the force of its compressed spring 73 to bring its shoulder 70 in front of the toe 69 of the sear-latch. The upward swinging movement of the transmitting-member 71 is effectively restrained by engagement of its forward end with the underside of the resiliently-held washer 81, which acts as a buffer to prevent the transmitting-member from striking the toe 69 of the sear-latch sharply and with such force as to cause the end of the transmitting-member to rebound. That is to say, by providing the buffer-means, the shoulder 70 of the transmitting-member is moved upwardly with restraint into position for full locking engagement with the toe 69 of the sear-latch 66. Now, as the breech-bolt is advanced and locked in breech-closing position, the cocking-shoulder 38 of the firing-plunger 24 will be moved forwardly into engagement with the sear-shoulder 39 which, due to the moment force of the compressed firing-spring 26 acting thereon, tends to swing downwardly. However, any slight downward movement of the sear, and more particularly of its lug 62, serves to swing the toe 69 of the sear-latch forwardly into locking engagement with the shoulder 70 of the transmitting-member, as hereinabove described, whereby the sear is effectively held up in firing-plunger-cocking position. The elements of the firing mechanism are again in position for firing the firearm.

In order to facilitate the disassembly of the firearm, and more particularly the removal of

the breech-bolt from the receiver when the firing-pin is in its firing position, as shown in Fig. 3, the sear 41 is provided with the aforementioned downwardly - and - rearwardly - depending lever-arm 56, the lower extremity of which is adapted to engage against the back edge of the trigger-finger 34. Thus, by pulling forwardly on the finger-piece 91 of the trigger, the finger-portion 84 thereof is pivoted upwardly in a counterclockwise direction, thereby pivoting the lever-arm 56 of the sear in a clockwise direction so as to swing the nose 49 of the sear downwardly out of the path of movement of the breech-bolt, thereby enabling the latter to be pulled rearwardly out of the receiver.

In order that the firearm may be made safe, an L-shaped manually-operated safety-lever 92 is provided which, as indicated in Fig. 2, is pivotally mounted on the outside of the right-hand face 46 of the trigger-plate by the outwardly-extending end of the pivot-pin 72 of the transmitting-member, the upper arm of the lever having an elongated vertical slot 920 therein to receive the outer end of a pin 93 secured to the lower forward corner of a bolt-locking latch 94 which, in turn, is pivotally supported at its upper forward corner by the sear pivot-pin 42 on the right-hand side of the trigger-plate. Thus, a toggle-joint connection is made between the safety-lever 92 and the bolt-locking latch 94 such that when the safety-lever 92 is moved into safety "on" position, as hereinafter described, the bolt-locking latch will be automatically swung up into a position to lock the bolt-operating handle from rotation in a direction to unlock the bolt, as indicated by the broken lines in Fig. 5; and on swinging the safety-lever to its "off" position, the bolt-locking latch will be moved into its inoperative position, as shown by the full lines in Fig. 5. The upper arm of the safety-lever has a finger-engaging portion 96 which extends upwardly into a clearance-recess 97 in the receiver and from thence outwardly substantially perpendicularly thereto to facilitate engagement by the finger of the operator, the finger-engaging portion 96 being resiliently held normally in a forward or safety "off" position by the force of a safety-spring 98 acting to pull the pivot-pin 93 of the toggle-jointed safety-lever and bolt-locking latch forwardly in their respective inoperative positions.

It will be seen that by moving the finger-engaging portion 96 of the safety-lever forwardly and rearwardly respectively, the lower forwardly-extending arm 99 thereof will be moved into and from engagement with a pin 100 which extends transversely from the lower end of the sear-latch, as indicated clearly in Fig. 8, the free end of the forwardly-extending arm 99 being provided with a hook 101 for engaging in front of the transverse pin 100 of the sear-latch, to effectively hold the latter from swinging forwardly, or in a counterclockwise direction, to release the sear.

In this connection, it will be noted that in swinging the hook 101 of the safety-lever upwardly into engagement with the pin 100 of the sear-latch, a cam-surface 102 at the extremity of the hook engages and cams the pin rearwardly as the end of the hook passes thereover so that the toe 69 of the sear-latch is moved rearwardly slightly out of engagement with the shoulder 70 of the transmitting-lever 71, the slight rearward movement of the sear-latch serving simultaneously to move the sear-shoulder 39 upwardly into maximum contact with the cocking-shoulder

38 of the firing-plunger. The parts are held in their respective safety "on" position by the force of the firing-spring acting through the sear to pivot the sear-latch in a counterclockwise direction and hence hold the sear-latch pin 100 in the hook 101 of the safety-lever, this force being sufficient to overcome the force of the relatively-weak safety-spring 98 which is tensioned when the safety-lever is swung up into sear-latch-engaging position.

A modification of the fire-control mechanism of this invention is shown in Fig. 10, wherein the general arrangement of the sear, sear-latch, transmitting-lever and trigger and associated mechanism is substantially identical to that of the fire-control mechanism described above. In its modified form, however, the locking and unlocking of the sear 103 by means of the sear-latch 104 is effected by forming an integral substantially-vertically depending leg-portion 105 at the forward extremity of the sear, the lower rear corner of which comprises a relatively sharp nib 106, for the purpose hereinafter described, the upper portion of the back edge of the sear-leg 105 being blended into the bottom edge of the sear by an arcuate relief-recess 107 formed therein. The sear-latch 104 is pivotally mounted at its upper end in the vertical passage of the trigger-plate by means of a transverse pivot-pin 108 which is located rearwardly of the leg-portion 105 of the sear and substantially opposite the relief-recess 107 in the bottom edge thereof. The lower end of the sear-latch is normally urged to swing upwardly in a counterclockwise direction by means of a spring 109 engaged on the pivot-pin 108 of the sear-latch and having a forwardly-extending arm 110 engaging against the rear edge thereof, and a rearwardly-extending arm 111 adapted to engage at its lower end against the underside of one of the aforesaid spacer-beads of the trigger-plate. The front edge of the sear-latch 104 is provided with a shoulder 113 which is below the pivot-pin 108 and is adapted to be lockingly engaged by the nib 106 of the depending leg-portion 105 of the sear, for the purpose hereinafter described. The bottom edge 114 of the sear-latch is arcuate and intersects the back edge of the sear-latch to form a relatively-sharp toe 115. The latter is adapted normally, that is to say, when the firing-plunger is held in cocked position by the sear, to engage against the forwardly-facing shoulder 116 of a notch 117 formed in the upper edge of the transmitting-member 118 adjacent the forward end thereof. The latter is pivotally mounted at its rear end in the vertical passage of the trigger-plate and is adapted to be held up resiliently with its forward end in engagement with a buffer-washer 119 by means of a coil-spring 120 adjustably supported in the bottom of the trigger-plate and adapted to engage against the underside of the transmitting-member 118 forwardly of its pivot-pin. As in the previously-described fire-control mechanism, the rear end of the transmitting-member is provided with an upwardly - and - forwardly - extending knee-portion 121 adapted to be engaged by an upwardly- and-forwardly-extending finger-portion 122 of a trigger 123 pivotally mounted in the trigger-plate rearwardly of the pivotal supporting-means of the transmitting-member.

With the elements of the fire-control mechanism in their respective positions as shown in Fig. 10, the firing-plunger 124 is effectively held in cocked position by engagement of its cocking-

shoulder 125 with the rearwardly-facing shoulder 126 of the sear 103 which is held up in its cocking position by engagement of the sear-nib 106 with the shoulder 113 in the front edge of the sear-latch 104. The moment force of the compressed firing-plunger spring (not shown), which acts to pivot the sear-shoulder 126 downwardly out of engagement with the cocking-shoulder of the firing-plunger, is effectively resisted by engagement of the toe 115 of the sear-latch against the forwardly-facing shoulder 116 of the transmitting-member 118. On pulling the trigger 123 rearwardly, its forwardly-and-upwardly-extending finger-portion 122 moves the knee-portion 121 of the transmitting-lever forwardly in a clockwise direction, thereby depressing the forward end of the transmitting-member, and in particular its shoulder 116, out of engagement with the toe 115 of the sear-latch to release the latter, whereupon the sear-latch shoulder 113 is pivoted downwardly in a clockwise direction by the force moment of the compressed firing-plunger spring acting against the shoulder of the sear and transmitted thereby to the sear-latch below the pivot-pin thereof. Consequently, the unlatched sear 103 is pivoted downwardly in a clockwise direction to disengage its shoulder 126 from the cocking-shoulder 125 of the firing-plunger to release the latter and effect the discharge of the firearm. On disengaging the trigger 123, the transmitting-member 118 is urged to pivot upwardly in a counterclockwise direction by the force of its compressed spring 120, thereby pivoting the trigger 123 forwardly and elevating the forward end of the transmitting-member into engagement with the arcuate bottom edge 114 of the sear-latch 104. Since the toe 115 of the latter has been displaced rearwardly of the shoulder 116 of the transmitting-member and is held in its rearwardly-displaced position by the sear-leg 105, the sear being held in its depressed position by the overriding of the breech-bolt and firing-plunger, the toe 115 of the sear-latch is prevented from re-engaging the shoulder 116 of the transmitting-member. However, on retraction of the bolt and firing-plunger, the nose of the sear is freed, whereupon the sear is pivoted upwardly in a counterclockwise direction by the force of the compressed sear-spring 127, the sear-latch being pivoted forward freely in a counterclockwise direction by the force of its compressed spring 109 to re-engage its toe 115 in the notch 117 of the transmitting-member. Then, with the movement of the breech-bolt into breech-closing position, the cocking-shoulder 125 of the firing-plunger 124 re-engages the shoulder 126 of the sear to exert a force moment thereon tending to pivot the sear 103 in a clockwise direction, whereupon the toe 115 of the sear-latch is moved rearwardly slightly into locking engagement with the shoulder 116 of the notch 117, the fire-control elements being thus effectively locked in firing-plunger-cocking position.

As pointed out above, the elements of the modified fire-control mechanism are assembled generally in the relationship of the fire-control mechanism previously described, and hence the manually-operated safety-lever referred to above is adapted to be applied to the modified structure shown in Fig. 10, a transverse pin 128 being provided in the lower end of the gear-latch 104 for engagement by the forwardly-extending arm of the safety-lever, the hook of which (not shown) being modified to cammingly engage the back

edge of the pin 128, so as to positively hold the toe 115 of the sear-latch forwardly out of engagement with the shoulder 116.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. Trigger mechanism for bolt-action firearms, including in combination: a spring-pressed firing-member having a substantially-vertical forwardly-facing cocking-shoulder; a sear; sear-pivotal means located below and normally rearwardly of the said cocking-shoulder of said firing-plunger; a rearwardly-facing substantially-vertical sear-shoulder forwardly of said pivotal means; a trigger; lever mechanism interposed between said trigger and sear and movable independently thereof normally to hold the said rearwardly-facing sear-shoulder in cooperative engagement with the forwardly-facing cocking-shoulder of said firing-plunger against the force of its compressed spring and to release said sear-shoulder from engagement with the cocking-shoulder of said firing-plunger when said trigger is operated to discharge said firearm; and a sear-finger projecting rearwardly of the pivotal-means of said sear and arranged in juxtaposition to said trigger whereby displacement of said trigger in an abnormal direction of movement lowers the forward end of said sear to facilitate disassembly of the bolt from said firearm.

2. Trigger-mechanism for bolt-action firearms including in combination: a spring-pressed firing-plunger having a forwardly-facing cocking-shoulder; a sear; a sear pivotal means; a rearwardly-facing shoulder on said sear forwardly of said sear pivotal means, said rearwardly-facing shoulder being adapted normally to cooperatively engage the cocking-shoulder of said firing-plunger; a trigger; and coacting lever-means adapted to releasably hold said sear-shoulder in its normal position in cocking engagement with the cocking-shoulder of said firing-plunger against the force of the compressed firing-plunger spring, said coacting lever-means comprising a sear-supporting latch and a pivoted transmitting-lever interposed between said trigger and said latch, said latch being pivoted independently of said sear and being interposed between the latter and said transmitting lever and having a shoulder upon which said sear rests while engaged by the cocking-shoulder of said firing plunger, said shoulder forming a releasable engagement between said latch and sear, said latch being actuatable toward sear-releasing position solely by the compressive force of said firing-plunger spring acting through said sear and being normally releasably held against such movement by engagement with said transmitting-lever, said transmitting-lever being arranged to release said latch upon actuation of said trigger to permit said latch to be swung out of sear-supporting position by the force of said compressed firing-plunger spring, thereby releasing said sear from cocking engagement with said firing-plunger.

3. Trigger-mechanism for bolt-action firearms including in combination: a spring-pressed firing-plunger having a forwardly-facing cocking-

shoulder; a sear; sear pivotal means; a rearwardly-facing shoulder on said sear forwardly of said pivotal means, said rearwardly-facing shoulder being adapted normally to cooperatively engage the cocking-shoulder of said firing-plunger; a trigger; and coacting lever-means adapted to releasably hold said sear-shoulder in its normal position in cocking engagement with the cocking-shoulder of said firing-plunger against the force of the compressed firing-plunger spring, said coacting lever-means comprising a sear-supporting latch and a pivoted transmitting-lever interposed between said trigger and said latch, said latch being pivoted independently of said sear and being interposed between the latter and said transmitting lever and having a shoulder upon which said sear rests while engaged by the cocking-shoulder of said firing plunger, said shoulder forming a releasable engagement between said latch and sear, said latch being actuatable toward sear-releasing position solely by the compressive force of said firing-plunger spring acting through said sear and being normally releasably held against such movement by engagement with said transmitting-lever, said transmitting-lever being pivoted at a point remote from the point of engagement with said latch and being contacted by said trigger, upon actuation of the latter, adjacent the pivot point of said lever to effect trigger movement multiplying action, said transmitting-lever being thus arranged to release said latch upon actuation of said trigger to permit said latch to be swung out of sear-supporting position by the force of the compressed firing-plunger spring, thereby releasing said sear from cocking engagement with said firing-plunger.

4. Trigger mechanism for bolt-action firearms as defined in claim 3, wherein said sear supporting latch is free-swing on its pivot, said latch having a second shoulder adapted to be contacted by said sear upon movement of the latter toward its firing-plunger engaging position to swing said latch back into its normal position of releasable engagement with said transmitting-lever.

5. Trigger-mechanism for bolt-action firearms including in combination: a spring-pressed firing-plunger having a forwardly-facing cocking-shoulder; a sear; sear pivotal means; a rearwardly-facing shoulder on said sear forwardly of said sear pivotal means, said rearwardly-facing shoulder being adapted normally to cooperatively engage the cocking-shoulder of said firing-plunger; a trigger; coacting lever-means adapted to releasably hold said sear-shoulder in its normal position in cocking engagement with the cocking-shoulder of said firing-plunger against the force of the compressed firing-plunger spring, said coacting lever-means including a trigger-actuated transmitting-lever and a pivoted sear-supporting latch, said sear-supporting latch being arranged to be engaged by said transmitting-lever and held thereby in a position to support said sear in cocking engagement with said spring-pressed firing-plunger against the force of the compressed firing-plunger spring, said trigger-actuated transmitting-lever being arranged to disengage said latch upon actuating said trigger, the force of said compressed firing-plunger spring acting on said sear serving to swing said latch out of its sear-supporting position thereby releasing said sear from cocking engagement with said firing-plunger; and a sear-spring, said sear-spring being independent of said latch and arranged to engage said sear below said sear-

shoulder to return said sear to its normal position for re-engagement of said cocking-shoulder with said firing-plunger.

6. Trigger-mechanism for bolt-action firearms including in combination: a spring-pressed firing-plunger having a forwardly-facing cocking-shoulder; a sear; sear pivotal means; a rearwardly-facing shoulder on said sear forwardly of said sear pivotal means, said rearwardly-facing shoulder being adapted normally to cooperatively engage the cocking-shoulder of said firing-plunger; a trigger; coacting lever-means adapted to releasably hold said sear-shoulder in its normal position in cocking engagement with the cocking-shoulder of said firing-plunger against the force of the compressed firing-plunger spring, said coacting lever-means including a trigger-actuated transmitting-lever and a pivoted sear-supporting latch, said transmitting-lever being interposed between said trigger and said latch and arranged to multiply the movement of said trigger for actuating said latch, and resilient means arranged to engage said transmitting-lever normally to urge said transmitting-lever into engagement with said sear-supporting latch so as to hold the latter in a position to support said sear in cocking engagement with said spring-pressed firing-plunger against the force of the compressed firing-plunger spring, said trigger-actuated transmitting-lever being arranged to disengage said latch upon actuating said trigger, the force of said compressed firing-plunger spring acting on said sear serving to swing said latch out of its sear-supporting position thereby releasing said sear from cocking engagement with said firing-plunger; and a sear-spring, said sear-spring being independent of said latch and arranged to engage said sear below said sear-shoulder to return said sear to its normal position for re-engagement of said cocking-shoulder with said firing-plunger.

7. Trigger-mechanism for bolt-action firearms including in combination: a receiver having a trigger-plate fixedly mounted thereon; a spring-pressed firing-plunger reciprocably mounted in said receiver and having a forwardly-facing cocking-shoulder; a sear; pivotal means arranged to mount said sear in said trigger-plate; a rearwardly-facing shoulder on said sear forwardly of said sear pivotal means, said rearwardly-facing shoulder being adapted normally to cooperatively engage the cocking-shoulder of said firing-plunger; a trigger pivotally mounted on said trigger-plate; coacting lever-means adapted to releasably hold said sear-shoulder in its normal position in cocking engagement with the cocking-shoulder of said firing-plunger against the force of the compressed firing-plunger spring, said coacting lever-means comprising a sear-supporting latch pivotally mounted in said trigger-plate, a transmitting-lever pivotally mounted on said trigger-plate between said trigger and said latch and arranged to multiply the movement of said trigger for actuating said latch; resilient means arranged to engage said transmitting-lever normally to urge said transmitting-lever into engagement with said sear-supporting latch so as to hold the latter in a position to support said sear in cocking engagement with said spring-pressed firing-plunger against the force of the compressed firing-plunger spring, said trigger-actuated transmitting-lever being arranged to disengage said latch upon actuating said trigger, the force of said compressed firing-plunger spring acting on said sear serving to swing said latch out of its sear-supporting position thereby releasing said sear from cocking engagement with said firing-plunger; and a sear-spring, said sear-spring being independent of said latch and arranged to engage said sear below said sear-

13

tion thereby releasing said sear from cocking engagement with said firing-plunger; and a sear-spring, said sear-spring being independent of said latch and arranged to engage said sear below said sear-shoulder to return said sear to its normal position for re-engagement of said cocking-shoulder with said firing-plunger.

HARRY H. SEFRIED, II.
